(57) **CLAIM**

The ornamental design for a stroller having a carrier as shown and described.

DESCRIPTION

FIG. 1 is a top, front, right perspective view of a stroller having a carrier in accordance with our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom view thereof.

Broken lines represent portions of the stroller having a carrier that form no part of the claimed design.

1 Claim, 7 Drawing Sheets
